UNITED STATES PATENT OFFICE.

JOSEPH A. YOUNG, OF BELLEVUE, IOWA.

COMBINED CUT-OFF AND STRAINER FOR WATER-PIPES.

No. 878,850.

Specification of Letters Patent.

Patented Feb. 11, 1908.

Application filed February 3, 1906. Serial No. 299,271.

To all whom it may concern:

Be it known that I, JOSEPH A. YOUNG, a citizen of the United States, residing at Bellevue, in the county of Jackson and State 5 of Iowa, have invented new and useful Improvements in a Combined Cut-Off and Strainer for Water-Pipes, of which the following is a specification.

My invention relates to a combination 10 strainer and cut-off for rain-pipes, and more especially in the nature of an improvement and addition to Letters Patent granted and issued to me on the 28th day of March 1901 and No. 674,993.

15 The following specification will set out in detail the improvements which constitute my invention, when taken in connection with the drawings accompanying the same and forming a part hereof.

20 Figure 1, is a perspective view of my device. Fig. 2, is a vertical section of Fig. 1. Fig. 3, is a side view of the screen or strainer removed. Fig. 4, is a perspective view of the cut-off proper taken from one side. Fig. 25 5, is a perspective view of the cut-off taken from the opposite side of Fig. 4. Fig. 6, is a plan view of the blank of the main-pipe. Fig. 7, is a plan view of a detail. Fig. 8, is a plan view of the valve. Fig. 9, is a plan 30 view of the blank from which is formed the waste spout. Fig. 10 is a modified form of a cut-off.

Like characters of reference denote corresponding parts in each of the figures.

35 Referring to the drawings 2 represents the body of the cut-off and consists of a sheet metal pipe 5 cut away at 8 for purposes presently to appear. Against the inside of the body 5 is secured at an angle to the body a 40 plate 10 shown in Fig. 6 and to one side of the body around the opening 8 is secured a waste-spout 12. This spout consists of a body with the ears or side plates 14 secured to the pipe 5 by the rivets 15 and also soldered to the pipe, and cut out in V shape at 45 16 and slightly bent towards each other so as to direct the water upon the screen. These ears or side plates furnish the walls or sides of the screen and strainer.

50 Against the inner side of the pipe 5 near its top is secured a screen 18 which extends downwardly at an angle to the pipe 5 and out some distance upon the top of the waste-

spout 12 to 20 and is set at a peculiar angle having a sharp incline from 22 to 24 and a 55 gradual slant to 25, then a slight slant toward the end 26.

By means of the peculiar bends in the screen and the position in which it is set, there is furnished more space between the 60 surface of the screen and the edge 21 of the pipe so that there will be less liability of any clogging from the leaves and other debris. And since the screen projects from the body and extends some distance along the upper 65 surface of the spout 12, there will be obtained a more extended surface for the screening of the water, and the screen will be securely sustained. Also the water will be fully screened before it passes into the cistern through the main pipe or into the waste 70 through the spout and none of the leaves or debris can possibly be carried either into the cistern or into the waste, preventing clogging of either pipe. 75

The screen is corrugated or ribbed at 27 and surrounded by a binding border 28 which is crimped and the metal pressed in around each of the wires that form the screen rigidly uniting the two. These 80 crimps in binding border also form pockets for the solder when soldered to the body, making the same to more firmly adhere.

The points on the body of the pipe 5 are bent inward at 30 for the purpose of directing the water from the binding around the edge of the screen in towards the center of the screen. 85

Within the spout 12 beneath the screen 18 is pivoted a valve or cut-off 32 which 90 consists of sheet metal bent, as shown in Figs. 4 and 5 and rounded at 34 to adapt it to engage beneath the plate 10, and prevent any water from escaping down the main-pipe 95 when the cut-off is turned to direct the water into the waste-pipe 12. It is also rounded at 35 so that when the valve is turned to cut off the passage of water through the spout 12 it will conform to the shape of the spout 12. It is also bent at both sides 36 and provided 100 with holes or openings 37 through which the operating lever 38 passes.

The manner of securing the valve 32 on the lever 38, consists in first cutting out an opening 29 provided with flanges 31 in the valve 105 and then bending the lever 38 into an oval

V shape at 40 and inserting the bent portion through the opening 29 and then pressing the flanges 31 between the bend 40; thus closing the opening 29. This does away with all the 5 solder or other securing means and rigidly holds the valve 32 upon the lever 38. The lever 38 passes through the openings on the sides 36 of the valve and is pivoted through the sides of the spout 12. The handle 42 is bent with 10 a hook 43 adapted to engage and be inserted in a hole 44 in the spout 12 and the hole 45 in one of the ears 14, so that when the cut-off crosses the passage from the main-pipe into the spout 12, the valve will be locked by the 15 insertion of the hook 43 in the hole 45 and when it is opened for the passage of the water through the spout 12 it will be locked by engagement with the hole 44. It will be seen by this mode of construction of the valve and 20 attachment of the valve to the lever that there will be no danger of the valve becoming loosened or affected by freeing and will always be rigidly secured to the lever. It will also be evident by this mode of construct- 25 ing the lever and pivoting it in the spout, that the valve will be securely locked whether it be opened or closed.

In Fig. 10 is shown a modified form of a cut-off having the same valve 32 mounted on 30 the same lever, but the main-pipe is bent at 50 and lower down the pipe is still further bent at 52 making an inverted Y shaped cut-off. The spout is attached to the main pipe by the ears 14 and the screen 18 is set in the 35 same manner as in the other figures. The valve 32 is pivoted so as to close and open the spout and main-pipe, but the locking holes or openings 44 and 45 with which the lever engages are, one through the main-pipe 40 and one through the spout.

Among the advantages of my invention over my former invention are the construction of the screen and the manner of setting it in the cut-off; the valve and the mode of 45 securing it to the lever together with means for locking the same, and the spout for carrying away the water, provided with ears forming the walls of the screen and also rigidly sustaining one end of the screen, or 50 strainer which projects from the body and in the described position that furnishes better and more extended means for screening the water. Another advantage will be noticed that by means of the bent portion 30 of the 55 main-pipe the water and debris are all directed toward the center of the screen causing a large saving of water and less liability of clogging.

Having now described my invention what I claim is:

1. In a cut off, a main pipe formed with an opening in its front wall, a tubular waste pipe secured at one of its ends to the main pipe surrounding the lower portion of the opening therein, integral side walls bent up 65 from the upper wall of the waste pipe thereby forming an intermediate opening in the upper portion of the waste pipe, a screen secured to the rear wall of the main pipe and extending through the upper portion of the 70 opening therein between said side walls and covering the opening in the upper portion of the waste pipe.

2. In a cut off, a main pipe formed with an opening in its front wall, a tubular waste 75 pipe secured at one of its ends around the lower portion of the opening in the main pipe, and being provided with an opening in its upper wall communicating with the opening in the main pipe, and integral side walls 80 for the opening in the waste pipe extending above the top wall of said waste pipe and formed of bent up portions of the top wall of the said waste pipe.

3. In a cut off, a casing, a valve therein 85 and an operating lever therefor, said valve being formed with a flanged opening, said lever being bent to form a doubled portion, said doubled portion being inserted in said opening and secured by said flanges. 90

4. In a cut off, a casing, a valve therein and an operating lever therefor, said valve being formed with a flanged opening, said lever being doubled upon itself to form a bent portion, said bent portion being inserted 95 in said opening and secured by said flanges, said flanges being disposed between the doubled portion of the lever.

5. In a cut off, a main pipe, a waste pipe secured to the main pipe, a valve provided 100 with three openings one flanged substantially at the center, said valve being set at the junction of the main pipe and waste pipe and being adapted to be oscillated to open or close the main pipe and waste pipe, a 105 lever having its ends passed through two of said openings and through one of said pipes, the central portion of the lever being formed with a bent portion and secured by closing the said flanges upon the same. 110

In testimony whereof I affix my signature, in presence of two subscribing witnesses.

JOSEPH A. YOUNG.
